UNITED STATES PATENT OFFICE.

CHARLES H. KNOBBS, OF PHILADELPHIA, PENNSYLVANIA.

PORT LIGHT.

1,412,409.

Specification of Letters Patent. Patented Apr. 11, 1922.

Application filed May 19, 1919, Serial No. 298,068. Renewed April 6, 1921. Serial No. 459,015.

To all whom it may concern:

Be it known that I, CHARLES H. KNOBBS, a citizen of the United States, residing at Philadelphia, in the county of Philadelphia and State of Pennsylvania, have invented 5 new and useful Improvements in Port Lights, of which the following is a specification.

The invention relates to ships and more 10 particularly to the port-lights thereof, and has for an object to provide a port-light providing ventilation to an interior portion of a vessel when the port-light is open and also adapted for the passage of light to an 15 interior portion of a ship.

The invention comprehends among other features the provision of a port-light which is particularly adapted for use on the hulls of vessels or other parts of a ship, for the 20 purposes of providing ventilation or light, and to this end, contemplates a glass frame which can be arranged in an open or closed position, relative to its supporting port-light frame, a suitable cover being also provided 25 which latter element can be closed upon the glass frame, all of the parts when closed, providing a locked structure which will exclude the light from the interior of the vessel and also prevent the ingress of water.

In the further disclosure of the invention, reference is to be had to the accompanying drawings, constituting a part of this specification, in which similar characters of reference denote corresponding parts in all the 35 views, and in which,

Figure 1—is a perspective view of the improved port-light, showing the glass frame and cover in closed position.

Figure 2—is a perspective view of the 40 same showing the glass frame closed and the cover in open position.

Figure 3—is a side elevation of the same showing both the glass frame and the cover in open positions and spaced from each 45 other.

Figure 4—is a vertical sectional view taken centrally through the structure with the parts in closed position as shown in Figure 1.

Figure 5—is a horizontal sectional view 50 taken through the hinge for the glass frame and cover.

Figure 6—is a detail sectional view taken through one of the clamping and locking 55 devices for securing the glass frame to the port-light frame.

Figure 7—is a similar view taken through one of the locking lugs and devices securing the cover to the glass frame.

Figure 8—is a fragmentary front elevation with parts of the locking device broken away to show the manner of guiding the glass frame into closed position.

Figure 9—is a fragmentary perspective view showing a slightly modified form of 65 locking device.

Referring more particularly to the drawings, the numeral 10 indicates a port light frame, of substantially circular form, suitably bolted to the side 11 of a vessel or the 70 like to register with an opening 12 therein. Suitably seated in the outer face of the port light frame is an annular gasket 13, and adjacent thereto are the equally spaced integral locking lugs 14, each of which is 75 formed with a cam like under surface 15 inclined to the plane of the face of frame 10. The port light frame is also formed with a plurality of spaced outwardly projecting lugs 16 having bearings to receive a 80 pintle 17 which extends loosely through elongated openings 18, formed in hinge members 19 which project from the periphery of a glass frame 20 having a suitable glass or light 21 secured therein. The 85 glass frame 20 can be swung upon the port-light frame 10 through the medium of the pintle 17 and when the glass frame fits down upon the port light frame, an annular seat 22 thereof will bear against the gasket 13 90

A cover 23 is provided for the glass frame 20 and the cover is formed with a plurality of hinge elements 24 having elongated openings 25 in which the pintle 17 loosely engages, so that the cover 23 and glass frame 20 95 are both pivoted to swing upon the pintle 17 which is therefore common to both the glass frame and the cover. The cover 23 is provided with a gasket 26 which when the cover is closed down upon the glass frame, causes 100 the gasket to bear against the annular rim or seat 27 on the glass frame. It should be particularly noted that the pintle or hinge connection between the glass frame and the port-light frame, and the cover and the port-light frame, provided for independent swinging movements of the glass frame and the cover in a common path. It will be noted however that because of the elongated openings in the hinge members of the glass frame 110 and cover, the said glass frame and the cover, each has an independent movement apart

from its swinging thereof, upon the port-light frame; that is to say, the glass frame after being swung at an angle to the plane of the port-light frame, can also be moved 5 toward or away from the gasket 13 against which the glass frame is adapted to seat and so also the cover 23 apart from its swinging movement relative to the glass frame and the port-light frame, can be moved bodily to 10 ward or away from the rim 27 of the glass frame. The object in providing independent movement of the glass frame, apart from its swinging movement and so also with the cover, is to permit of uniformly and securely 15 clamping the glass frame evenly against the gasket on the port-light frame and therefore also to permit of clamping the cover uniformly and evenly against the rim 27 of the glass frame. If the glass frame and cover 20 were only mounted to swing, it would be impossible to obtain an equal clamping pressure entirely around the particular gaskets and thus an effective joint in each instance would not be obtained. 25 To effect the proper clamping and locking of the glass frame with the port-light frame, a plurality of clamping and locking devices or dogs 28 are provided, each having a suitable handle 29 and a projection 30. 30 These clamping and locking devices 28 are suitably mounted to swing upon ears 31, projecting from the glass frame and the projections 30 are adapted to engage with and seat in the particular lugs 14 formed on the 35 port-light frame, with faces of the projections 30 adapted to bear against the inclined or cam-like surfaces 15 of the lugs, thus insuring a positive clamping of the glass frame against the gasket 13, regardless of 40 the hinged or swinging connection of the glass frame with the port-light frame and therefore when the handles of the clamping and locking devices 28 are actuated, the projections 30 operating over the inclined surfaces 15 of the lugs 14, will not only clamp but securely lock the glass frame uniformly and evenly against the gasket on the port-light frame. 45 In a similar manner the cover 23 is provided with ears 32 which pivotally support clamping and locking devices 33, having handles 34 and projections 35, the latter being adapted to engage in and with lugs 36 on the periphery of the glass frame and also 50 adapted to have faces thereof, operate over inclined surfaces 37 on the lugs so that the gasket 26 will be uniformly pressed down upon the annular rim 27 of the glass frame and the operation of the clamping and locking devices 33 will insure a positive locking 55 of the cover to the glass frame, regardless of the hinged or swinging connection of the cover relative to the port-light frame. 60 It may be here stated that it is important 65 to have the glass frame slip readily into po-

sition to seat upon the gasket of the port-light frame and to effect this result, edges 38 of the lugs 14 are rounded off to form guides, tending to guide the glass frame into proper seating position, projections 39 of the clamping and locking devices or dogs 28, being adapted to extend into recesses or cupped out portions 40 in the face of the port-light frame. 70

From the foregoing description, it will be 75 seen that the glass frame can be swung relative to the port-light frame and independently of the cover and that the cover can be swung relative to the port-light frame independently of the glass frame; further that 80 the glass frame can be secured in clamped and locked position upon the port-light frame independently of the cover, and that the cover can be clamped and locked to the glass frame independently of the clamping 85 and locking relation of the glass frame to the port-light frame. Still further it is to be noted that with this construction, the glass frame swings in the path of swinging movement of the cover and vice versa, this being 90 due to the provision of a single hinge element to which both the cover and the glass frame are common. It is to be observed that after the glass frame has been swung from an open to a closed position, the operation of 95 the clamping and locking devices move the glass frame forward or against the port-light frame to the clamping position, this movement being one which is in the plane of the port-light frame so that the glass frame 100 is capable of a swinging movement relative to the port-light frame and also capable of a backward and forward movement relative to the port-light frame. Likewise, the cover can be swung to an angle at a plane of the 105 glass frame and independently moved backward or forward relative to the glass frame in order that the cover can be clamped uniformly around its entire periphery to the 110 glass frame, when the clamping and locking devices thereof are engaged with the particular lugs 36, provided for the purpose. 115

In Figure 9, I show a slightly modified form of my device and in which instead of 120 providing handles 29 for the clamping and locking devices 28 and handles 34 for the clamping and locking devices 33, I merely substitute in place of the handles, enlarged portions 41, respectively, which may, in cross section, be of a hexagonal construction and will, when an ordinary or particular form of wrench is applied thereto, permit of actuating the clamping and locking devices 28, 33, to lock the glass frame to the port-light frame or the cover to the glass frame or vice versa. This particular form 125 of construction is employed in cases where port-lights are placed within the reach of passengers on a ship, who, if the clamping and locking device were provided with han- 130

dles, might endeavor to operate the port light or unloosen the cover or glass frame and thus result in subsequent damage or injury to the vessel, in the event of a heavy sea 5 or storm, enabling the water to pass through between the cover and glass frame, or the glass frame and the port-light frame, to the interior of the vessel.

It will be understood that I do not limit 10 myself to the particular form of construction set forth in the specification and illustrated in the drawings, that various slight changes may be made without departing from the spirit of the invention and that the scope 15 thereof is defined in the appended claims.

Having described my invention, I claim,—

1. A port light comprising a port light frame, a glass frame loosely hinged upon the port light frame and movable into open 20 or closed relation thereto, a gasket on the port light frame in position to engage the glass frame when the latter is closed thereupon, locking lugs on the port light frame, pivoted locking levers on the glass frame 25 adapted for engagement with the said lugs to clamp the glass frame in closed position against the said gasket and cooperating guide members upon said frames for centering the glass frame upon the gasket of 30 the port light frame.

2. A port light comprising a port light frame, a glass frame loosely hinged upon the port light frame and movable into open or closed positions relative to the port light 35 frame, a gasket on the port light frame adapted to have the glass frame clamped down thereupon, a loosely hinged cover for the glass frame and movable into open or closed positions relative to the latter, a gasket arranged between the cover and glass frame and adapted to engage with both of said members when the cover is arranged in closed position upon the glass frame, cooperating guide members upon said glass 40 frame and port light frame for centering the glass frame upon the gasket of the port light frame, means for clamping the said glass frame in closed position against the gasket on the port light frame, cooperating guide 45 members upon the cover and glass frame for centering the cover upon the glass frame, and means for clamping the cover in closed position against the glass frame.

3. A port light, comprising a port light 55 frame, a glass frame mounted to swing on the port light frame and also movable independently bodily axially of and toward or away from the port light frame, and means for clamping the glass frame in closed position upon the port light frame, said clamping means being constructed and arranged to center the glass frame upon the light port frame.

4. A port light comprising a port light 65 frame, a glass frame loosely hinged upon

the port light frame to swing thereon and also independently movable bodily toward or away from the port light frame, one of said movements of the glass frame being in the peripheral plane of the port light 70 frame and the other at an angle thereto, means for locking the glass frame in closed position upon the port light frame, said locking means being constructed with devices to guide the glass frame into central 75 closed position upon the port light frame.

5. A port light comprising a port light frame, and a glass frame loosely hinged upon the port light frame, one of said frames being formed with cam faced lugs 80 and centering recesses or sockets, and the other of said frames having movably mounted upon it locking dogs formed with projecting ends adapted to engage said recesses or sockets to centre the glass frame upon 85 the port light frame, and said dogs being adapted to engage said cam faced lugs for locking the frames together in closed position.

6. A port light comprising a port light 90 frame formed with cam faced lugs and centering recesses or sockets, a glass frame loosely hinged upon the port light frame, locking dogs movably mounted upon the glass frame and formed with projecting 95 ends adapted to engage said sockets of the port light frame for centering the glass frame thereon and said cam faced lugs for locking the glass frame in closed position.

7. A port light comprising a port light 100 frame formed with cam faced locking lugs, a glass frame loosely hinged upon said port light frame, locking dogs mounted upon said glass frame in position to engage said cam faced lugs, a cover loosely hinged upon 105 the port light frame in position to engage and close the glass frame, and independent locking devices arranged between the cover and glass frame.

8. A port light comprising a port light 110 frame having cam faced locking lugs, a glass frame having loose joint hinge connection with said port light frame, means distinct from said hinge connection for centering said glass frame upon said port light frame 115 and a plurality of independently adjustable locking dogs movably mounted upon said glass frame in positions to engage said locking lugs.

9. A port light comprising a port light 120 frame, a glass frame mounted to swing on the port light frame, a cover hinged on the port light frame to swing in the path of movement of the glass frame with or independently of the latter, and means for automatically guiding the glass frame axially central of the port light frame and the cover axially central of the glass frame, said means including locking dogs having ends adapted to cooperate with recesses formed 125 130

respectively in the port light frame and the glass frame, whereby the glass frame is brought into locking position on the port light frame and the cover is moved into 5 locking position on the glass frame.

10. The combination in a port light, of a port light frame having spaced lateral projections and spaced lugs formed with cam faces, a glass frame having radial apertured 10 ears and radial lugs formed with cam faces, locking devices journaled in said ears and

having lateral projections to engage the cam-faced lugs of the port light frame, a cover having radial apertured ears, locking devices journaled in said ears and having 15 lateral projections to engage the cam-faced lugs of the glass frame, and a pintle connecting the glass frame and the cover to the lateral projections of the port light frame.

15 In testimony whereof I affix my signature. 20

CHARLES H. KNOBBS.
